No. 267

J. Green and G. Warren, Design for Stoves

STOVES & FURNACES

Cooking Stoves & Ranges

Patented Feb. 19, 1850.

Ms. A. 67

J. D. Green and George Warren of Troy N.Y.
Letters Patent No 267. Dated Feby 19th 1850 —

The schedule referred to in these Letters Patent and making part of the same.

So all whom it may concern:

Be it Known that we, Jeremiah D. Green and George Warren of Troy, in the County of Rensselaer and State of New York, have invented or produced a new and ornamental design for a Cooking Stove of which the following is a full description, reference being had to the accompanying drawing thereof in perspective which forms part of this specification.

Our Cooking Stove, as represented, is of the usual form; the sides, top, and bottom plates being plain, and the ornamental design being confined to the various doors with which the sides are fitted, and to the feet by which it is supported. The top and bottom of the stove project considerably beyond the sides and their projecting edges are covered with plain mouldings. The doors are each deeply, paneled and are surrounded with heavy mouldings; the depressed portion of each panel is filled with an arabesque figure, the largest being on

the oven door) composed of leaves c radiating from a central elliptical fillet b: this same figure is repeated on all the panels, being varied in its proportions to suit the size and configuration of the panels to which it is applied, but always retaining its central fillet, and radiating leaves.

The stove is supported on four feet A ornamented with arabesque leaves c bordered by voluted scrolls i i.

What We claim as our invention and desire to secure by Letters Patent is the configuration and arrangement of the ornamental figures on the door panels and feet of the stove, constituting together a design for a stove.
